corporation of New York

Application September 15, 1937, Serial No. 163,944

7 Claims. (Cl. 250—20)

This invention relates to radio receiving apparatus and more particularly to improvements in radio receivers disclosed in Matzner Reissue Patent No. 18,796, in which a flashing stop signal is provided, showing when the tuning apparatus has arrived at the proper position to select any one or more of a number of chosen stations for which the receiver has previously been adjusted to give such a signal, applied to receivers of the super-heterodyne type.

10 For the purpose of this description, such stations are herein termed "flash stations", because they may be selected by a flash signal of the receiver without reference to logs, newspaper guides, or the like, after having once been adjusted or keyed in the flash mechanism of the receiver.

The increasing power and crowding of transmitting stations in the ether channels, together with the increased amplification and selectivity 20 of receivers, making increased accuracy and exactness of tuning necessary, has introduced difficulties in the manufacture and operation of flash tuning receivers. Among these may be mentioned the necessity for greater accuracy and 25 greater flexibility in adjustment of the flash controlling mechanism, resulting from the reception of stations at points considerably closer together on the dial, and the liability of the apparatus to give a signal when no station is received, or even 30 a signal for a different station from that being received, resulting from drifting of the oscillator frequency away from its assumed value, with consequent mistuning of the desired flash station.

35 It is an object of this invention to provide a receiver with generally improved flash tuning operating characteristics, particularly of the super-heterodyne type. More specifically, it is an object of this invention to provide such a receiver 40 in which mistuning is reduced and a greater tuning tolerance provided; with which a larger number of both local and distant stations may be easily and quickly keyed for flash tuning reception; to provide a receiver which, when operating by flash tuning, will not respond to stations other than those previously adjusted or 45 keyed for flash tuning, and which will be silent except when receiving a flash station, even when being tuned through flash stations; to provide for simplified manufacture and adjustment of the receiver for flash tuning operation, both originally and in case it is desired to change the adjustment of the receiver from one previously 50 made, as to any one or more of the transmitting

stations for which a flash tuning signal is desired; to provide a generally improved mechanical and electrical structure facilitating the adjustment of the receiver for a large number of flash stations and better observation of the adjustment of the receiver to any particular flash station, as well as improved observation of the entire choice of flash tuning stations, and to provide such a receiver which will operate either with or without the flash tuning characteristics, 10 as desired.

Still other objects and advantages of our invention not specifically stated above will be apparent from the specification.

The features of novelty which we believe to be 15 characteristic of our invention are set forth with particularity in the appended claims. Our invention, however, both as to its fundamental principles, and as to its particular embodiments, will best be understood by reference to the specification and accompanying drawings, in which:

Fig. 1 is a schematic or block diagram of a receiver according to our invention;

Fig. 2 (parts *a*, *b* and *c*) is a detailed circuit diagram of a receiver in accordance with our invention;

Fig. 3 is a front view of a dial of a receiver in accordance with our invention;

Fig. 4 is a sectional view of the dial of Fig. 3;

Fig. 5 is a detailed circuit diagram of the muting apparatus for rendering the receiver silent between flash tuning stations;

Fig. 6 is an elevation view of the contact mechanism for producing the flash signal at desired dial settings;

Fig. 7 is a top plan view thereof;

Fig. 8 is a sectional elevation of lines 8—8 of Fig. 6; and

Fig. 8a is a perspective view of a tool which may be used for "logging" flash stations;

Figs. 9 and 10 are curves illustrating the operations of the discriminator network.

Our invention is disclosed herein by way of example, as embodied in a super-heterodyne "all-wave" receiver arranged to operate from a commercial source of alternating current. It will be understood, however, that this is by way of example, as certain of the principles of our invention may be applied to battery operated receivers, as well as to those designed to cover a greater or smaller range of frequencies, and those not involving the superheterodyne principle.

In accordance with our invention we prefer to provide a receiver having a dial of the clock type, in which a pointer moves over a dial, all of which

is exposed to view, with means for mounting tabs showing the call letters of the various stations, and a travelling flash signal light mounted in position to selectively illuminate any one only of the call letter tabs at a time; with means for controlling the oscillator frequency to provide for exact and precise tuning of the desired signal over a considerably greater dial setting than would otherwise be possible; with simple means for preventing or reducing response of the loud speaker except when the receiver is tuned to a flash station (herein called "muting"); with selective controls for eliminating or affording flash tuning as may be desired; with the circuits arranged to prevent sudden and violent crashes of sound when a station is tuned in, but to cause it to build up to desired volume relatively slowly; and with improved correlation of controls to permit the desired features of operation to be obtained with a simple set of operating controls.

For purposes of clarity, the receiver will first be described as a whole, and its operation described generally, after which the various parts will be described more in detail.

Referring now more particularly to Fig. 1, 1 designates any suitable form of antenna from which a signal voltage is drawn, and which may be amplified at its own frequency in an amplifier with which there may be associated selecting circuits of any desired type. After the desired amount of amplification, the signals are fed to a mixer or first detector tube and mixed there with beat or heterodyne currents from an oscillator, and from which they emerge at a lower frequency (so-called beat or intermediate frequency) and are then amplified by lower frequency amplifier to the desired extent at the beat frequency.

These further amplified signals are then applied to a discriminator and detector network, the construction and operation of which will hereafter be described in greater detail. At this point, it suffices to note that the discriminator and detector network has a pair of output circuits, to one pair of which it supplies audio frequency or voice currents derived from a second detection or demodulation of the signal, and to the other of which it supplies a direct current voltage similarly derived, herein termed oscillator frequency control voltage, E_d , the magnitude of which is proportional, within limits, to the deviation of the intermediate or beat frequency being received from the calculated or design value, and the sign of which corresponds to the direction of such deviation.

For example, if the predetermined value of the intermediate frequency is 465,000 cycles, and the oscillator frequency so adjusted with reference to the incoming signal that the difference is exactly 465,000 cycles, the oscillator control voltage E_d will be zero. If the frequency difference between the signal and oscillator frequencies increases, because of drifting of either or both or if the dial be slightly mis-tuned, the voltage E_d will become, say, positive, and will increase in magnitude with increase of frequency difference, within limits which may be chosen as hereinafter explained.

On the other hand, should the frequency difference between the incoming signal and oscillator decrease, because of such drifting, or mis-tuning, E_d will become negative, and its magnitude will increase in value with the amount of departure, within the limits for which the design is chosen.

This oscillator control voltage is applied to an oscillator frequency control circuit, operating in

a manner to be hereafter described in detail, to cause a correction of the oscillator frequency by an amount such as to keep the intermediate frequency always at or very near the value to which the intermediate frequency portion of the receiver is resonant for any particular station. 5

The audio frequency output of the detector and discriminator network is supplied to a suitable audio frequency amplifier and after amplification, to the extent desired, to a suitable signal indicator such as loud speaker L. S. 10

For flash tuning, the dial 11 is constructed to receive a plurality of tabs 11a, 11b, 11c, etc., at various positions on the dial at which flash stations are received, as indicated by the pointer 11, 15 and these tabs carry the call letters of the particular station received at that dial setting.

In addition, we prefer to provide flash control apparatus, in the form of a dummy dial or "comb" 13, and a dummy pointer 13' carrying 20 spring finger 13'a, relatively movable with respect to each other, and synchronized with the dial and pointer, upon which the user may set up the adjustments to operate the flash signal at any desired dial settings. 25

Carried by the dummy dial or comb there are provided a number of contact fingers 13'a, 13b, 13c, etc., arranged to make contact with spring finger 13'a carried by the dummy pointer and thus to close a circuit between the comb and the 30 spring finger at predetermined dial positions. The position of the various fingers 13a, b, c, etc., is selected to correspond to the dial settings at which various flash stations are received, so that a circuit is closed between the dummy dial 13 35 and spring finger 13'a at each position of the dial at which a flash station is received, there being one such position only for each flash station, and the position of each flash station being different from that of other flash stations, as will 40 be understood.

When the circuit between comb and finger is closed at the position corresponding to that of a flash station, a circuit is operated including the flash indicator, which may be a lamp 16 whose 45 movements are synchronized with those of the pointer 11 and which is positioned so as to illuminate only the particular tab bearing the call letters of the flash station which is received at that point.

Preferably, the apparatus is constructed, in ways which will be described in more detail hereafter, so that the receiver is mute when adjusted for flash tuning, except when the dial is set for a flash tuning station. When the circuit is 55 closed between comb and spring finger, the flash indicator lamp 16 is energized, and circuits are operated which voice the receiver, so that when a tab is illuminated to show a particular flash station being received, the loud speaker will 60 produce the program of that particular station. 50

While the receiver is in a transition stage, being tuned away from one flash station to another, little or no response will be received, from other stations, or from static or noise. When the position for another flash station is reached the flash indicator will light, and the receiver will be voiced. However, in our preferred embodiment, it will not immediately begin to play, because a time lag is introduced by apparatus hereafter to 70 be described, which does not permit the receiver to come instantly up to the volume level to which it is set, but delays and graduates its response for a small time interval, of the order of a second. 65

This reduces acoustic shock, caused by loud 75

blasts of sound issuing suddenly from the loud speaker, and also permits tuning from one flash station through one or more intervening flash stations to the particular flash station then desired, without any response from intervening flash stations.

The correlation of the design of the discriminator network and control tube with that of the closure range of the comb and finger permits the desired flash station to be perfectly tuned over a considerably greater dial range than would be otherwise possible, and provides a latitude of adjustment for each dial setting which would otherwise be impossible to obtain.

Referring now more specifically to Fig. 2, 1 represents an antenna, which may be of the usual T or L type, or one section of a doublet, and 2 the other section of the doublet. 3a, 3b, 3c, 3d, 3e, 3f, 3g, 3h, and 3i represent various sections 10 of the wave-change switch which are operated in synchronism by a common control, to select the wave band desired to be received, sections 3a and 3b being associated with the antenna system, 3c and 3d being associated with the antenna system, 3c and 3d being respectively associated with the input and output of the R. F. amplifier preceding the mixer or translator tube, 3e with the input of the translator, 3f with the plate side of the oscillator, 3g with the grid side of the oscillator, and 3h and 3i with the flash tuning 20 control.

As shown, the switching system provides for four bands, of which the broadcast is the lowest in frequency and the receiver is shown with the 30 switches in position to receive that band. As the switches are rotated in a counterclockwise direction as observed in Fig. 2, the band frequency progressively increases, the inductances and capacities being appropriately adjusted in the 40 antenna, r. f. amplifier, translator and oscillator circuits. These switches may be arranged to provide a larger or smaller number of wave bands.

In the switch sections, where a plurality of blades are indicated, it will be understood that the 45 angular relation of the blades is fixed as indicated, and that such blades rotate with such angular relation unchanged. Likewise, where segments are shown, these rotate with the blades with their angular relations unchanged.

For broadcast frequencies, i. e. 500-1500 kilocycles, the doublet section 2 is preferably not used 50 as a doublet, the current path to ground being opened by wave change switch 3b, and section 2 being merely tied to section 1 as a capacity through coil 5c, which latter coil has no substantial effect at such frequencies. For the next higher band, the path to ground from section 2 is still opened by switch 3b, and section 2 is tied 55 to section 1 through coil 5d. For the two highest bands, however, the path to ground from section 2 is direct, and it will be noted that circulating currents between the two sections 1 and 2 can flow through coils 5c or 5d for the two higher 60 positions of the wave change switch, whereas for the two lower frequency positions of switches 3a and 3b, the two sections 1 and 2 feed in parallel 65 to the set through coil 5a or 5b.

The feed from coils 5a, 5b, 5c, and 5d is shown 70 as by inductive coupling to coils 6a, 6b, 6c, and 6d respectively in the grid circuit of the r. f. amplifier tube 11, the tuning circuit in each case being formed by one of the latter coils and its associated trimmer condenser shown adjacent but not numbered, and by tuning condenser, section 14a, 75 in parallel therewith, which condenser section is

one of the sections of the three-gang tuning condenser, consisting of sections 14a, 14b, and 14c, by which the desired station is selected.

It will be noted that for the two lower frequency bands, condenser 14a is short circuited by the 5 right hand segment of switch section 3c, but for the two higher bands, it is connected in series with condenser 14a between the control grid of 10 amplifier tube 11 and ground, thereby reducing the effective capacity of condenser 14a.

Radio frequency amplifier tube 11 is indicated as a pentode, but other types of tubes may be employed if desired. The anode or plate 11e is preferably connected to the blade of wave change switch section 3d, thence through coils 7a, 7b, 7c, 15 17, and to the conductor marked plus B line, depending on the position of the wave change switch.

The cathode of tube 11 may be connected to ground through resistances 15 and 16 in series and 20 alternating currents by-passed to ground through condenser 17. Resistance 16 may be short-circuited in one position of the section 17a of flash and selectivity control switch, the purpose and 25 operation of which will be hereafter explained.

Control grid 11b is preferably connected to the upper terminal of condenser 14a, whence it receives the signal voltage to be amplified. The screen grid 11c may be connected to a source of positive potential less positive than the plate, 30 and the suppressor grid 11b to the cathode as customary.

Coils 7a, 7b, 7c, and 7d are coupled, preferably inductively, to coils 8a, 8b, 8c, and 8d respectively, and, similarly to the input circuit of tube 11, each 35 coil may have its trimmer condenser associated with it, and be tuned by section 14b of the gang tuning condenser. Condenser 14b is arranged similarly to condenser 14a and has a similar purpose.

As will be understood, the circuit so far functions as an amplifier of incoming signals at their own frequency, the various circuits being band-tuned or broadly made responsive to frequencies in the desired band by the wave-change switch, 45 and the input circuits of tubes 11 and 12 being more or less sharply tuned by the sections of the gang tuning condenser.

The frequency of the signals may be now lowered in tube 12, which is herein shown as a tube 50 of the known penta-grid converter type, having cathode 12a, electrodes 12b, 12c, 12d, 12e, and 12f, and anode or plate 12g. This tube is not connected in the usual manner for such tubes, but electrode 12b may be connected to function as a 55 control electrode by being connected to the upper terminal of condenser 14b to receive signal voltage. Electrodes 12c and 12e may be connected together and to the screen return line, to which 11c is connected. Electrode 12d may be connected to 60 the oscillator and translator control circuit in a manner to be hereafter more fully described, and received therefrom the oscillator frequency oscillations which are mixed with the incoming signals to produce the beat frequency currents.

At this point, it may be noted that coils 6a, 6b, 6c and 6d may be connected through resistance 59 to the grid return line, connected to ground through by-pass condenser 19a. Similarly, coils 70 8a, 8b, 8c, and 8d may be connected to the grid return line on the opposite side of resistance 59. The connection of the grid return line and its operation will be described hereafter.

Electrode 12d may be connected to ground through resistance 19, and the common point of 75

coils 8a, 8b, 8c, and 8d may be connected to the ground point of resistance 19 through by-pass condenser 20.

The plate 12g may be connected through output coil 22a, with its associated trimmer condenser, not numbered, to the plus B line, and through a by-pass condenser to ground.

The currents of lower or beat frequency are fed to coil 22b coupled to coil 22a, and which may 10 have connected in series therewith coil 24 and resistance 25. The trimmer condenser, not numbered, may be connected to the upper terminal of coil 22b, and to the blade of section 17b of the flash and selectivity switch, the first and second 15 (clockwise) contacts of which section are connected to the lower terminal of resistance 26a, while the third is connected to the lower terminal of coil 22b. The effect of this is that when the 20 flash and selectivity switch is on the first two contacts, the tuning is broader than when the switch is on the third contact. It will be understood that this circuit is tuned to the beat frequency instead of to the actual signal frequency.

The beat or intermediate frequency amplifier 25 may comprise one or more stages such as tube 23, herein shown, like tube 11, as a pentode, having cathode 23a, control grid 23b, screen 23c, suppressor 23d, and anode 23e. Control grid 23b may be connected to the upper terminal of coil 30 22b, screen 23c to the screen return line, the suppressor 23d to the cathode, and anode 23e through coil 24a and its associated trimmer condenser to the plus B line. Cathode 23a may be connected through self-biasing resistance 26a shunted by 35 by-pass condenser 26 to ground.

The intermediate frequency currents flowing in coil 24a are supplied to coil 24b in the well known manner, and thence to the discriminator and detector network, through coil 24c connected 40 in series with coil 24b, and adjustable tuning condenser 25, and the common point of condensers 25 and coil 24c may be connected to the grid return line. Coils 26 and 27 (which are preferably identical) may be connected in series, and 45 shunted by adjustable condenser 28 and by adjustable condensers 29 and 30 in series, the intermediate point between said condensers being grounded. Coil 24c may be inductively and 50 reversely coupled to coils 26 and 27 respectively and a direct connection may be provided between the upper terminal of condenser 25 and the common 55 point of coils 26 and 27.

Two rectifiers may be provided; i.e., tubes 31 and 32, here indicated as triodes, although diodes 55 may be employed. The tubes may comprise cathodes 31a and 32a, control grids 31b and 32b, and anodes 31c and 32c, the cathodes being connected through condenser 33, and the anodes through resistance 34 and 35. The anode of tube 60 32 may be grounded as indicated, and the anode of tube 31 connected to the oscillator control tube line and to switch contact 108, which latter circuit is described later. The anode of tube 21 supplies the oscillator frequency control voltage 65 Ed, through resistance 36, and the latter is connected to ground through by-pass condenser 37.

The mid-point of resistors 34 and 35 supplies the audio frequency signal resulting from demodulation of the intermediate frequency signal, 70 which audio frequency signal may be further amplified by the audio frequency amplifier.

The operation of the discriminator and detector network will now be described. The secondary system consisting of coils 24b, 24c and condenser 75 25 in series is tuned to the best frequency and the

tertiary system, comprising coils 26 and 27 and tertiary tuning condenser 28, in parallel with which are condensers 29 and 30 in series and the various capacities of tubes 31 and 32, is likewise tuned to the beat frequency.

In such an arrangement, the voltages developed at resonance in coils 26 and 27 are 180° displaced in phase (because the direction of coupling to coil 24c is reversed between them) and both said voltages are 90° displaced with respect to the 10 voltage in coil 24b.

Because of the connections, it will be seen that tubes 31 and 32 rectify respectively the vector sums of the voltages across coils 24c, 24b and 26 (tube 31) and coils 24c, 24b, and 27 (tube 32), 15 which voltages are 90° displaced in phase. One of these voltages maximizes below resonance, as in curve A, Fig. 9; the other maximizes above resonance as in curve B, Fig. 9. Which does which depends on the direction of the respective 20 couplings between secondary and tertiary systems.

If these two tertiary voltages be separately rectified and then combined, the resultant voltage curve has the form shown by the full and dotted 25 line curves of Fig. 10, the direction of slope being determined by the direction of coupling between secondary and tertiary. This voltage, it will be seen, is proportional in magnitude and corresponds in sign to the direction of the departure 30 of the beat frequency currents from the frequency to which the system is tuned; i.e., the design frequency of the secondary and tertiary system, which is the desired beat frequency.

This departure may be caused by drifting of the 35 transmitter or oscillator frequency or both, or other causes but in any event, it may be utilized to control the oscillator frequency to cause a corresponding correction which will restore the beat frequency to the desired value, and thus maintain the desired signal exactly in tune.

How this may be done will now be explained. The local oscillations may be generated by oscillator tube 38, which may be a triode, or other type of tube, herein shown as having a cathode 38a, control grid 38b, and anode 38c. The grid may be provided with grid leak 39 connected to grid, cathode and ground, and grid condenser 40.

The grid circuit may comprise any one of coils 9a, 9b, 9c, or 9d, selected by section 3g of the 50 wave-change switch, and the plate circuit the appropriate one of coils 10a, 10b, 10c, and 10d similarly selected by section 3f of the wave-change switch. Each of these coils may be grounded through its appropriate adjustable condenser and shunted by its appropriate trimmer condenser, not numbered, and each may be inductively coupled to its corresponding grid coil 9a, 9b, 9c, or 9d.

This system as will be understood, forms a 60 feed back oscillator, and it will be noted that it is tuned on the plate side, rather than the grid side, as customary. This has been found to increase stability of the oscillator and lessens the disturbance which we call "motor-boating."

It will be noted that variable tuning of the oscillator frequency for station selection is obtained through small capacity condenser 69, to the third section 14c of the three-gang tuning condenser, which is in parallel with the oscillator 70 plate coil. In the lowest frequency position of the wave-change switch, (farthest clockwise) adjustable condenser 41 is in series with tuning condenser section 14c and serves to reduce its effective capacity, and in the next two higher posi- 75

tions it is shorted out, having no effect, while in the highest frequency position (farthest counter-clockwise) it is again in series with the tuning condenser section 14c, reducing its effective 5 capacity.

The anode of the oscillator tube 38 is preferably connected to the plus B line through resistances 42 and 43, the mid-point of which is grounded through condenser 44.

10 As so far described, the oscillator is not affected by the oscillator control voltage Ed. How this control is exercised will now be described.

In parallel with the plate inductance 10a of the oscillator, we provide the oscillator frequency 15 control tube 45. The circuits of this tube are so arranged that this tube operates like a variable inductance (or condenser) under the control of the voltage Ed, increasing to lower the oscillator frequency when the beat frequency increases, 20 and decreasing to raise the oscillator frequency when the beat frequency lowers, and thus maintaining the beat frequency substantially constant at all times in spite of drifting of either signal or oscillator frequency, or both, or of 25 inaccurate tuning.

While various types of tubes may be used for this purpose, we prefer to use a pentode, comprising cathode 45a, control grid 45b, screen grid 45c, suppressor 45d, and anode 45e. The anode 30 45e may be connected to the upper terminal of coil 10a and to the cathode 45b through resistance 46 and condenser 48.

Condenser 47 may be connected from control grid 45b to the common point of condenser 48 35 and resistance 46, and said grid may be likewise connected through resistance 52 to the anode of tube 31 which furnishes the oscillator frequency control voltage. Cathode 45a may be grounded through resistance 49 for self-biasing, by-passed 40 by condenser 50.

The operation of tube 45 is as follows: Assuming a voltage across inductance 10a, that voltage will also be across resistance 46 and condenser 48, which are in effect in parallel there- 45 with (the series condensers between coil 10a and cathode 45a and ground being in effect of no impedance for the oscillator frequency) and the phase will be the same as that across condenser 47, which has one terminal connected to condenser 48. Condenser 48 may be very small compared to condenser 47 (1,000 m. m. f. for 47 and 15 m. m. f. for 48) and resistance 46 of the order 50 of 50,000 ohms.

Under such conditions, the voltage across coil 55 10a will also be in effect across resistance 46 and condensers 47 and 48, and the current through coil 10a will lag the voltage across coil 10a by substantially 90°; but the current through resistance 46 and condenser 48 will be 60 substantially in phase with the impressed voltage (the resistance of 46 being high with respect to the impedance of condenser 48. The voltage across condenser 48 and also condenser 47 will lag the current in those condensers by substantially 90°. The voltage across condenser 47 is in effect that between the cathode and control grid of oscillator frequency control tube 45, and is therefore 180° out of phase with the current in coil 10a.

70 The tube plate current is in phase with the control grid voltage, since the tube plate impedance may be regarded as a resistance, and the voltage drop across it due to change in the plate current is in phase with the control voltage, and 75 hence with the voltage across inductance 10a.

The current through tube 45 is, however, controlled by the voltage Ed, increasing or decreasing as that voltage departs from zero.

Thus, the tube may be effect regarded as either a variable inductance or a variable con- 5 denser, the inductance or capacity of which varies with the voltage impressed upon it, and as such, corrects any deviation in the oscillator frequency produced by oscillator 38, or changes the oscillator frequency when the beat frequency 10 changes because of drift of signal frequency, within limits determined by the circuit constants, and thus maintains the beat frequency at or very near the desired value, and preserves exact tuning under conditions where it would otherwise 15 not exist.

It will ordinarily be desirable to control the gain of the radio frequency amplifier end of the receiver inversely in proportion to the strength 20 of received signals, to maintain a more or less constant volume output level from the loud speaker. This may be done by separating the audio frequency currents to some extent from the demodulated current output of the discrimi- 25 nator and detector network, and thus obtaining a more nearly pure direct current, which may be applied as a bias voltage to the control grids of tubes 11 and 12 to regulate their gain.

This may be done by filtering the demodulated 30 output of the discriminator and detector network, by feeding the demodulated currents through resistance-capacity filter made up of resistance 55, shunted by condensers 56 and 57 in series, the common point of condensers 56 and 57 being grounded. Audio frequency currents 35 may then be drawn from the common point of resistance 55 and condenser 57, while more nearly pure direct current may be drawn from the common point of resistances 35 and 55, and applied as a grid bias to tubes 11 and 12, through 40 the conductor marked "grid return line", in series in which may be provided resistances 58 and 59. Resistance 58 may be very high, as 1 megohm, resistance 59 somewhat lower, as 45 100,000 ohms.

As will be understood, the stronger the signal, the greater will be the negative bias applied to the control grids of tubes 11 and 12 and the lower their gain will be.

The audio frequency currents may be further 50 amplified by the first A. F. amplifier tube 60, which may be a triode if desired. Manual volume control may be obtained in any suitable manner, for instance by passing the audio frequency currents to ground through condenser 55 55 61 and resistance 62 in series, and tapping off the desired part of the audio frequency voltage drop through resistance 62 by adjustable contact 63, connected through condenser 66 to the control grid of tube 60.

A second stage of audio frequency amplification 65 may be provided by tube 64, also shown as a triode, although any suitable type may be employed, coupled to tube 60 in any suitable manner, as by condenser 65 and resistance 66, which latter may be grounded as shown. Tone control may be provided by condenser 67 connected between ground and an adjustable point on resistance 66 and operating in the known manner. 70

A third or output stage of amplification has been shown, employing a phase changer tube 67 and a pair of output tubes of the 6N6G type, 70 75 76 and 77, feeding a loud speaker 72, but since these tubes per se, and their circuit connections are

well known in the art, they are not described in detail.

A rectifier and filter system for supplying direct current to the various tube electrodes is also shown on the drawings, but since this part of the apparatus is well known in the art, it is not described in detail, being illustrated by conventional and well understood symbols.

It will be understood that the receiver so far described will operate to receive signals of the frequency to which it is tuned, and that the operation of the discriminator and oscillator frequency control tube affords more latitude in the dial settings without mistuning than would otherwise be possible. How this is correlated with the flash tuning apparatus, and how that apparatus is constructed and operated, will now be described.

The dial 11 is diagrammatically illustrated in Fig. 1, traversed by a pointer 11', to indicate the adjustment of the tuning elements. Positioned on the dial face at appropriate positions we provide a plurality of tabs 11a, 11b, 11c, etc., each of these tabs being preferably transparent, or translucent, and having marked thereon the call letters of the transmitting station which is received when the pointer 11' points to that particular tab, and arranged to be illuminated only at that position of the pointer.

At the same time, sufficient illumination of the dial as a whole is provided to see the setting of the pointer at all times, but without detracting from the flash signal which is given when the dial pointer reaches the position for a flash station. The details of construction by which this is made possible are shown in Figs. 3 and 4, and will now be described.

In order to eliminate parallax in reading the position of the pointer, mirror zones are provided on the dial. In Fig. 3 annular zones b and d may be mirror surfaces, while the other zones may be opaque in appearance. The various graduations and indications to be shown by the dial, with the exception of the call letters of flash stations, may be etched on the rear surface of the front dial glass 130, and filled with a suitable pigment.

The front surface of the rear dial glass 130 may then be sprayed lightly with a suitable paint, such as bronze, except over the areas where other coloration is desired. The layer of paint is made just sufficiently thick so that such portions of the dial appear opaque when viewed from the front of the dial with no light behind it. The rear of the dial is preferably completely shielded against extraneous light by a housing 135, the inside of which may be painted black. To provide the mirror surface for the mirror zones, a brightly polished disk of suitable metal 131 may be mounted behind the front glass dial 130, and both may be backed up by the rear glass disk 132.

General illumination of the dial may be secured by edge effect by placing a lamp 136 within the hollow shaft 89, which is provided with narrow circumferential slots at the plane of the dial. Stray light is prevented from escaping the outer end of the shaft by the pointer, which is held on the end of the shaft by a cap which fits snugly in position around the shaft.

With the dial so constructed, all figures and graduations are plainly observable when the receiver is positioned so that the dial is illuminated by light falling on the outer face of the dial from the front. At the same time, sufficient illumination is provided so that all figures and graduations, and the pointer are clearly observable

when the room is dark and the only light is that furnished by the center light 136, which, although not observable itself, nevertheless renders the dial and pointer clearly readable.

Behind the dial, and carried by the shaft 89 there may be provided a bracket 81 extending parallel to the pointer 11'. The outer extremity of this bracket carries a lamp socket 83, in which there is mounted a small lamp 16.

A demountable opaque hood or thimble 16a may be mounted upon lamp 16, and this hood may be provided with a longitudinal narrow slit 16b facing the dial, to permit the light from lamp 16 to shine through the dial and illuminate the particular tab which is in front of lamp 16, at the time it is lighted.

Extending around the rim of the dial we may provide a U-shaped strip 85 having spring fingers 85a extending inwardly on the face of the dial, and similar fingers 85b extending inwardly on the rear of the dial. Preferably fingers 85b are staggered or offset with reference to fingers 85a, and the spacing and angular relation of the slots between the fingers is so arranged that the tabs may be slipped under the fingers 85a at any point on the periphery of the dial at which a desired station is received.

The outer section of the dial where the tabs are placed preferably appears opaque except at the area in front of the slit 16a, when the lamp 16 is lighted, at which area enough light passes through the dial to render the call letters on the tab clearly legible and the appearance of such light signals that the receiver is tuned to that station.

Lamp 16 is lighted only when the tuning control is adjusted to receive any one of a number of flash stations for which the flash control is previously set or keyed. This flash control is provided by flash control apparatus shown diagrammatically in Figs. 6, 7, and 8, and comprises a "comb" or dummy dial 13, from the periphery of which there extend, at the positions corresponding to the dial setting for each desired flash station, teeth 13a, 13b, 13c etc.

Rotatable with pointer 11' we may provide a dummy pointer 13', carrying at its extremity a spring finger 13'a, arranged to engage each of the teeth 13a, 13b, 13c etc., when the tuning control is adjusted to the corresponding position. The comb 13 may conveniently be mounted on the rear plate 86 of the gang tuning condenser, assembly by bolts 88 and 89, and the finger or dummy pointer may be secured to the rear end of the condenser shaft 87 which may project through the plate 86 for that purpose.

The comb is preferably constructed of two identical stampings having a periphery a little more than a semi-circle. The periphery is notched to provide a multiplicity of teeth, 13a, 13b, 13c, etc., and the teeth are bent over at substantially right angles to the plane of the stamping. The peripheral width of the teeth and the spacing between them is so chosen that when the complete comb is formed, by rivetting two stampings together back to back, the teeth of each stamping lie opposite the space between the teeth of the other.

The spring finger 13'a may be mounted on bracket 90 angularly adjustable on arm 14 and held in adjusted position by bolt 91'. This adjustment permits the obtaining of good contact between contact finger 13'a and such of the fingers 13a, 13b, 13c, etc., as may be bent out into the plane of the comb, while preventing con-

tact between finger 13'a and the other fingers. The closure of the circuit so made energizes the lamp 16 to give the flash tuning signal, and may also control other circuits as will be hereafter described, to voice the receiver, which when operating on flash tuning, is preferably mute except when tuned to a flash station.

To adjust or key the receiver for flash stations, the procedure is as follows: the receiver is allowed to operate for a sufficient length of time to reach temperature equilibrium. Then, with the receiver controls set for non-flash operation, the dial settings for the various stations for which flash operation are determined, the particular tooth on the comb 13 which is opposite contact portion of spring finger 14a is marked for each flash station.

The marked teeth are then bent until they extend outwardly in the plane of the comb, and for this purpose the tool illustrated in Fig. 8a will be found useful. It may comprise a strip of metal having its opposite extremities bent at right angles in opposite directions as at 91 and 94. A narrow slot 92 may be formed in the end 91a, which slot fits over and embraces a single tooth at a time of the comb, and permits it to be bent into contacting position to engage finger 13'a, without danger of bending teeth other than the one desired.

With the selected teeth bent outward as explained, the receiver controls may now be set for flash operation, and the appropriately marked tabs placed under spring fingers 85a at the previously determined dial settings for the flash stations for which the receiver has been keyed. It may be noted that additional stations may be keyed at any time, in the same way, or if it is desired to eliminate from flash operation a previously keyed station, this may be done by simply bending down its tooth on the comb, and removing its tab from the dial.

It will be understood that without the use of the discriminator and detector network and the oscillator frequency control system, the flash control system would be very critical in adjustment, because even a slight mistuning would result in side band suppression, and corresponding distortion, and this in turn would require practically "razor edge" adjustment of the spring finger 13'a with reference to the comb, which would in turn render the receiver more sensitive to drifting of the oscillator or signal frequency. The apparatus herein disclosed eliminates these difficulties, and permits a relatively coarse adjustment of finger 13'a with reference to the comb, permitting the incoming signal to be received perfectly, without mistuning, over an appreciable width on the dial, much wider than would otherwise be possible, and thus permits quicker and easier tuning, while it eliminates the possibility of distortion resulting from mistuning.

The circuits by which the receiver is muted between flash stations will now be described. While these circuits are included in the complete diagram of Fig. 2, for clarity they are separately shown in Fig. 5.

The various circuit changes which occur when a flash station is tuned in are made by the relay having an actuating winding 101, movable blades 104 and 105 insulated from each other but movable together, front contact 109 made by front blade 105, and back and front contacts 107 and 108 made by blade 104. The relay blades are spring biased to back contact (voice) position,

and moved into front contact (mute) position by energizing coil 101.

The receiver is voiced when the relay is on back contact position, and mute in front contact position. When the circuit is open between finger 13'a and comb 13 (mute), a circuit exists from -B through the field winding 159 of the loud speaker, thence through actuating winding 101 of the relay and resistance 103 in parallel, and through resistance 102 to ground. This attracts the relay to front contact (mute) position. In this position, the oscillator frequency control voltage output Ed of the discriminator and detector network is grounded by blade 104, against front contact 108, the energizing circuit of lamp 16 is opened by blade 104, and blade 105 closing against front contact 109 applies a relatively high muting bias to the grid of the first audio frequency amplifier tube 60 through the circuit from -B through resistance 110, front contact 109, blade 105 to the lowest frequency contact of section 3h of the wave change switch, to the blade of said section, to flash contact 121 of section 120a of flash and selectivity control switch 120, to the blade thereof, thence through resistances 122 and 126 to the point between winding 101 and resistance 102.

From the common point of resistances 122 and 126 to ground there may be provided condenser 124, from the opposite terminal of resistance 122 condenser 123 to ground, and from the common point of resistances 122 and 126 a connection through resistance 125 to the control grid of tube 60, the first audio frequency amplifier. With the muting relay on front contact position, and flash control switch 17a set for flash operation and with the dial turned away from flash stations, the receiver will be mute.

When finger 13'a contacts any one of the fingers 13a, b, c, etc., of the comb, relay actuating winding 101 is short-circuited as follows: from winding 101 through resistance 102 to ground, to the comb, to finger 13'a, to low frequency contact of band switch section 3i, to the blade thereof, to blade of flash and selectivity switch section 120b, to fixed contact in position shown, to the opposite side of winding 101. The relay is thereupon closed by spring action against its back contacts, opening the muting bias circuit at front contact 109, ungrounding the Ed line at contact 208, and closing the circuit through lamp 16 as follows: ground, blade 104, back contact 107, lamp 16, secondary 108 (which may be a special transformer separate from the power transformer, or an additional secondary winding) to ground.

The receiver is now voiced and will respond to incoming signals. It should be noted, however, that a small interval of time is required for the charge upon condenser 124 to be dissipated, this condenser having been charged to the muting bias voltage. By selecting the desired time constant by choice of the values of resistances 122 and 126 and the capacity of condenser 124, this time interval may be established at the desired value, for example, one second. The effect of this is that in tuning rapidly, one may pass through one or more flash stations in reaching the desired flash station, and the receiver will not respond to such stations because there is not time for condenser 124 to discharge.

When the desired station is reached, and the station selector left on the position for the desired station, this condenser gradually discharges and the station gradually builds up to the volume 75

determined by the setting of the volume control. Wave change switch section 3h serves to open the muting bias circuit at positions other than the lowest frequency band, while section 3i opens the circuit around the relay actuating winding which otherwise would be closed at flash positions of the dial, and the relay is continuously held in front contact position. This renders lamp 16 inoperative to give a flash signal, but while the relay is in muting position the muting bias circuit is now open and the receiver is voiced at any position of the dial, and the Ed line is grounded, and the correction voltage is not applied to the oscillator control tube.

15 Flash and selectively switch sections 120a and 120b which are arranged for gang operation with switch sections 17a and 17b, likewise open the muting bias circuit and the circuit around the relay actuating winding respectively, just as with wave change switch sections 3h and 3i, although the flash and selectivity gang switch is operable independently of the wave change switch.

20 So arranged, flash tuning is available only on the broadcast band, but it will be understood that switches, 3h and 3i may be omitted if flash tuning is desired on all bands.

25 It will be observed that in the arrangement shown, flash tuning is available only in the broadly tuned condition, as established by switch section 17b, and that with flash operation, the receiver operates at maximum sensitivity as established by switch section 17a, but it will be understood that we may omit switch sections 120a and 120b if desired, or arrange them so that flash operation may be had for both broad and sharp tuning, or either, as desired.

30 While we have disclosed certain preferred embodiments of my invention, it will be understood that modifications and changes may be made without departing from the spirit and scope of our invention, as will be understood by those skilled in the art.

We claim:

- 40 1. In a tuning indicator for a radio receiver or the like, a tuning element, means for adjusting said tuning element, a luminous indicator carried by said adjusting means for movement therewith, means for silencing the receiver during tuning operations, and means actuated by said adjusting means for simultaneously energizing said luminous indicator to indicate the tuned condition of the receiver and rendering said silencing means inoperative.
- 45 2. In a tuning indicator for a radio receiver or the like, a tuning element, means for adjusting said tuning element, a luminous indicator carried by said adjusting means for movement therewith, means for silencing the receiver during tuning operations, means actuated by said adjusting means for simultaneously energizing said luminous indicator to indicate the tuned condition of the receiver and rendering said silencing means inoperative, said last mentioned means having a time delay means incorporated therein whereby the receiver may be tuned through a relatively strong signal without producing audible response thereto.
- 50 3. In a tuning indicator for a radio receiver

or the like, a tuning element, means for adjusting said tuning element, a luminous indicator carried by said adjusting means for movement therewith, means for silencing the receiver during tuning operations, means actuated by said adjusting means for simultaneously energizing said luminous indicator to indicate the tuned condition of the receiver and rendering said silencing means inoperative, electrical means for maintaining the tuning of the receiver at the frequency selected initially by operation of the tuning element and operating automatically to correct for frequency drift.

4. In a tuning indicator for a radio receiver or the like, a tuning element comprising an oscillator, means for adjusting said tuning element, a luminous indicator carried by said adjusting means for movement therewith, means for silencing the receiver during tuning operations, means actuated by said adjusting means for simultaneously energizing said luminous indicator to indicate the tuned condition of the receiver and rendering said silencing means inoperative, and electrical means for preventing frequency drift.

25 5. In a tuning indicator for a radio receiver or the like, a tuning element, means for adjusting said tuning element, a luminous indicator carried by said adjusting means for movement therewith, means for silencing the receiver during tuning operations, means actuated by said adjusting means for simultaneously energizing said luminous indicator to indicate the tuned condition of the receiver and rendering said silencing means inoperative, said last mentioned means comprising an electro-magnetic relay.

30 6. In a tuning indicator for a radio receiver or the like, a tuning element, means for adjusting said tuning element, a luminous indicator carried by said adjusting means for movement therewith, means for silencing the receiver during tuning operations, means actuated by said adjusting means for simultaneously energizing said luminous indicator to indicate the tuned condition of the receiver and rendering said silencing means inoperative, said last mentioned means including an electro-magnetic relay, biased to voice the receiver and electro-magnetically actuated to silencing position.

35 7. In a tuning indicator for a radio receiver or the like, a tuning element, means for adjusting said tuning element, a luminous indicator carried by said adjusting means for movement therewith, a switch having an element carried by said adjusting means for movement therewith and arranged to be closed at predetermined positions of said adjusting means, means for silencing the receiver during tuning operations, means actuated by said adjusting means for simultaneously energizing said luminous indicator to indicate the tuned condition of the receiver and rendering said silencing means inoperative, said last mentioned means including an electro-magnetic relay having an energizing coil short circuited by closure of said switch.
